MEANS FOR SHIELD TUNNELLING

Alferd Donald Gratton Wilson, Buckhurst Hill,
EnglandApplication February 6, 1945, Serial No. 576,491
In Great Britain February 3, 1944

3 Claims. (Cl. 61—85)

1

This invention relates to a means for shield tunnelling.

In known methods of tunnelling it is common to use a shield of the mechanical excavator or other type to effect or assist the excavation and thereafter to support the ground whilst the lining is being erected within the tail of the said shield.

The object of the present invention is to speed up and cheapen tunnel driving by an improved method which consists in employing a combination of two shields, or an excavating device and a trailing shield so that excavating may proceed simultaneously with the erection of the lining in the trailing shield.

In the accompanying drawing which diagrammatically illustrates an embodiment of this invention:

Figure 1 is a longitudinal section, on line I—I of Figure 2, and,

Figure 2 is a transverse section (the right-half being a section on line II—II, the left-half being a section on line III—III) of Figure 1.

According to this invention, which will be described with reference to the use of a leading or digger shield 1, and a trailing or main shield 2, the leading shield 1 which may be of any ordinary construction except that it is unprovided with the usual tail, and having at its front end a rotary cutter 3, is furnished around the circumference of its rear face with a plurality of hydraulic rams 4, the rear or outer ends 5 of which are adapted to bear against thrust blocks or a thrust plate 6 provided on the front face of the trailing shield 2.

The trailing shield 2, is of larger diameter than the leading shield 1, but is otherwise of similar construction thereto being provided with a plurality of rams 7 the rear or outer ends of which are furnished with shoes 8 adapted to bear against a part of the lining erected behind the trailing edge of the shield, such for example as the joist 9.

In operation, when the leading shield 1 has reached the end of its run and the rams 4 are fully extended as shown in Figure 1, the rams 4 are then retracted, after which the rams 7 of the trailing shield 2 are extended thereby forcing said shield forwardly the cutting edge 10 thereof trim-

ming the cut made by the leading shield 1. The lining of the tunnel thus formed may be effected in any known manner to the rear of the trailing shield as the latter is moved forward.

5 What I claim is:

1. Tunnelling device comprising a leading shield of substantially cylindrical form carrying on its front cutting means, a plurality of rearwardly directed hydraulic rams arranged along

10 the periphery of said leading shield near the rear edge thereof, a substantially cylindrical trailing shield provided adjacent its front edge with abutments forming bearings for the free rear ends of said rams, the latter in their fully

15 collapsed positions having a length to prevent the front edge of the trailing shield from reaching the rear edge of the leading shield so that the two shields are independent of one another except that the trailing shield provides the reaction for the forward movement of the leading shield.

2. Tunnelling device, as claimed in claim 1, in which the trailing shield has a diameter exceeding that of the leading shield so that its front 25 edge operates to trim the cut made by the leading shield.

3. Tunnelling device, as claimed in claim 1, including shoes on the free rear ends of said hydraulic rams, said trailing shield being provided 30 at a short distance behind its front edge with an inwardly projecting annular flange against which said shoes bear.

ALFORD DONALD GRATTON WILSON.
